UNITED STATES PATENT OFFICE

2,646,327

DESK OR TABLE TOP CONSTRUCTION

Fritz A. Saaf, Aurora, Ill., assignor to All-Steel Equipment Inc., a corporation of Illinois

Application December 6, 1949, Serial No. 131,429

4 Claims. (Cl. 311—107)

1

This invention relates to a desk or table top having rounded corners and a molding, and the principal objects of the invention are to provide an improved form and construction for such tops; to facilitate the construction and assembly of the top; and to provide improved means for securing a finish molding to the perimeter of the top.

More specifically, the invention relates to a desk or table top comprising a sub-top and a filler top, both being pan shaped and provided with side flanges that overlap when the pans are fitted together. The corners of the pans are formed by a drawing operation after an arcuate portion of each corner has been removed. A molding retainer not only secures the pans together, but also receives a strip of pliant molding material that obscures the joined pans and presents a finished appearance to the desk or table top.

In the particular embodiment shown in the accompanying drawings:

Fig. 1 is a fragmentary, perspective view of one corner of a desk top constructed in accordance with this invention, the corner portion being broken away to more clearly illustrate the form of the several parts which are assembled to make the desk top with its ornamental edging;

Fig. 2 is an enlarged exploded view of the corner portions of the several parts which are assembled to form the desk top;

Figs. 3 and 4 are fragmentary portions of the sheet metal stampings from which the sub-top and filler-top parts, respectively, are formed; and

Fig. 5 is an enlarged, fragmentary, sectional detail of the improved desk top, the section being taken on the line 5—5 of Fig. 1.

A desk top constructed in accordance with this invention comprises a sub-top 6 and a filler-top 7 respectively formed from sheet metal stampings 6a and 7a and secured together in opposed nested relationship and around the perimeter of which is secured an ornamental edging or molding, generally designated 8.

The sheet metal stampings 6a and 7a, from which the sub-top 6 and filler-top 7 are respectively formed, have the four corners cut away along inwardly extending, angularly disposed lines 9 and 10, and an intermediate arcuate line 11. The cuts 9 and 10 are disposed at right angles to each other and extend transverse to the edges 12 and 13 of the corners of the respective stampings. The arcuate cut 11, between the cuts 9 and 10, is formed on an axis substantially coincident with the intersection of the planes of the cuts 9 and 10. For the stamping 7a, the juncture of the cuts 9 and 10 and the edges 12 and 13 of that stamping are rounded, as indicated at 14 in Fig. 4.

2

Inwardly of and parallel to the respective stamping edges 12 and 13 are rows of spaced apertures 15 which, in the subsequently assembled sub- and filler-tops 6 and 7, come into registration to receive screws 16 by which the two tops are secured together and the ornamental edging or molding 8 is secured in place around the perimeter of the desk top.

The perimetrical portions of each of the stampings 6a and 7a between the arcuate corner cuts 11 are bent over to form transverse flanges 17 and 18 for the sub-top 6, and 19 and 20 for the filler-top 7. The bend of these flanges is along lines 21, as shown in Fig. 3, slightly inward from the base of the cuts 9 and 10. Thus, in the forming of the flanges 17 and 18, and 19 and 20, the portion of the stamping intermediate the cuts 9 and 10, concentric with the arcuate cut 11, is likewise folded over to form an arcuate flange 23 on the sub-top and an arcuate flange 24 on the filler-top, which flanges connect and are continuous with the respective flanges 17 and 18 and 19 and 20.

The flanges 17 and 18 for the sub-top 6 are again bent along lines 22 so that their perimetrical portions form inwardly extending flanges 25 and 26, respectively, disposed parallel to the body of the sub-top 6. Also, the flanges 17 and 18 are offset slightly inward from the lines 21 so as to form a ridge or bead 27 coextensive with the respective flanges 17 and 18.

In forming the rounded corners for the sub- and filler-tops, the flanges 17, 18, 19 and 20 are first bent down, and then suitable drawing dies form the arcuate flanges 23 and 24. This provides a nicely rounded, bent-over corner, of simple, yet sturdy, construction.

In order to appropriately reinforce the perimetrical portions of the assembled sub- and filler-tops 6 and 7, Z-shaped bars 28 and 29 are inserted between and bonded to the flanges 25 and 26 and the body of the sub-top 6, substantially co-extensive with the respective flanges 17 and 18, as most clearly shown in Fig. 5. In addition to the reinforcing Z-bars 28 and 29, other suitable reinforcing bars are arranged between the sub-top 6 and filler-top 7, as is shown and explained in co-pending application, Serial No. 697,760, filed September 18, 1946, now U. S. Patent No. 2,560,400.

The sub- and filler-tops 6 and 7 are assembled, as most clearly shown in Figs. 1 and 5, with the flanges 17 and 18 of the sub-top 6 nesting within the flanges 19 and 20 of the filler-top 7, and with the upper edges of the flanges 19 and 20 closely adjacent to the ridge or bead 27 on the sup-top 6, if not in actual contact therewith.

After these top sections are assembled, a sheet of linoleum 30, or other suitable material, is laid on the body of the sub-top 6, and glued thereto,

with its perimeter coextensive with the ridge 27 and beveled, as shown in Fig. 5. The molding 8 is then applied. It comprises a retaining member 31 and an ornamental member 32, the former comprising a flexible strip of extruded metal, preferably aluminum. It is made channel-shape, with the transverse parts or flanges 33 and 34 of arcuate form. The upper longitudinal edge is enlarged and formed with an inwardly disposed inclined shoulder 35 which mates with the 10 beveled edge of the linoleum or composition top 30 and is flush therewith.

The arcuate form of the transverse parts 33 and 34, of the channel strip 31, provide pockets 36 and shoulders 37 which serve to hold the ornamental strip 32 on the strip 31 with the outer face of the ornamental strip 32 flush with and forming a continuation of the outer faces of the arcuate-shaped transverse parts 33 and 34.

The ornamental strip 32 is made of extruded or molded pliant material, preferably in the nature of a synthetic material. As herein shown, it is of arcuate form with the exterior face grooved or otherwise rendered ornamental. The opposite longitudinal edges are recessed so as to provide tongues 38 which are adapted to extend into the pockets 36 and abut the shoulders 37 so as to secure the ornamental strip 32 to the retaining strip 31.

The retaining strip 31 is secured around the perimeter of the desk top by screws 16 entering the registering apertures 15 in the assembled sub- and filler-tops 6 and 7. The strip, being formed of flexible material, may be bent to closely fit the rounded corners of the desk top so that, if desired, a single strip of material may extend entirely around the desk or table top.

The ornamental strip 32, being of pliant material, is secured in place by simply inserting the tongue 38 along one edge into the corresponding pocket 36 of the retaining strip 31, and then using a suitable tool to slightly reduce the arc of the strip 32 and allow the opposite tongue 38 to be pressed into place in the opposite recess 36. To facilitate the insertion of the strip 32, it is preferably provided with an internal channel 39, which gives the strip greater flexibility, and accommodates the fastening screws 16.

I claim:

1. A desk or table top comprising a pair of sheet metal plates each of which has the four corners cut away along angularly disposed lines, extending transversely inward from the respective edges which normally meet to form the corners of said plates, and along an arc between said angularly disposed cuts, said plates having the perimetrical portions thereof between said corners bent at right angles to the plane of said plates to form transversely disposed flanges and having the perimetrical portion of said plates intermediate said cuts also formed to provide transversely disposed arcuate flanges connecting and continuous with said first-mentioned flanges, said flanged plates being superimposed with the flanges on one plate nesting within the flanges on the other plate.

2. In a desk or table top, a channel strip adapted to be applied to the margins of said top, the transverse parts of the strips being arcuate-shaped and converging toward each other so as to form opposed pockets extending longitudinally of said strip along the lateral edges, a molding of pliant material arcuate in cross section recessed

along its lateral edges to form a tongue and a shoulder, said molding being secured to said strip by having said tongues seated in said pockets and said shoulders abutting the edges of said transverse strip parts with the outer face of said strip flush and concentric with the arcuate outer faces of said transverse strip parts and means disposed between said strip and molding to secure said strip and molding to the desk or table top.

3. A desk or table top comprising, a pair of sheet metal plates each of which has the four corners cut away along angularly disposed lines, extending transversely inward from the respective edges which normally meet to form the corners of said plates, and along an arc between said angularly disposed cuts, said plates having the perimetrical portions thereof between said corners bent at right angles to the plane of said plates to form transversely disposed flanges and having the perimetrical portion of said plates intermediate said cuts also formed to provide transversely disposed arcuate flanges connecting and continuous with said first-mentioned flanges, said flanged plates being superimposed with the flanges on one plate nesting within the flanges on the other plate, a flexible channel strip the opposed faces of the transverse parts of which slightly converge toward each other, means extending through said strip intermediate said faces for securing said strip and flanges together, and a molding of pliant material secured to said strip by yielding engagement of its lateral edges with the converging faces of said transverse parts of said strip.

4. In combination with a desk or table top, a molding comprising a flexible channel strip, the transverse parts of which converge toward each other to form opposed pockets extending longitudinally of said strip along the lateral edges, means for securing the web of the channel strip to the edge of said desk or table top, and a strip of pliant material mounted in said channel strip and masking said fastening means, said pliant strip being recessed along both lateral edges to form a tongue and shoulder on each lateral edge with said tongues seated in said pockets and said shoulders abutting the edges of said transverse parts, whereby the pliant strip is resiliently locked within the channel strip.
